UNITED STATES PATENT OFFICE.

WILLIAM ALLAN, OF DUNDEE, SCOTLAND.

INTERNAL-COMBUSTION ENGINE.

Application filed March 3, 1927, Serial No. 172,445, and in Great Britain October 6, 1926.

This invention relates to internal combustion engines of what are known as the "two stroke" type, and embodies a novel construction the principal feature of which is that 5 the power stroke is divided between a normally reciprocating piston and a reciprocating working cylinder in which said piston operates, whereby air for scavenging and the mixture constituting the charge are precompressed and ports are controlled to admit 10 air and mixture to precompression cylinders to exhaust the products of combustion, and to transfer the precompressed air and mixture to the working cylinder.

15 Perfect balance may be ensured as regards reciprocating masses by varying the relative or proportionate strokes of the piston and reciprocating working cylinder.

The invention can be applied to vertical, 20 horizontal, inclined or radial engines, either of the single or multi-cylinder class and may, with advantage be applied with cylinders in tandem, or opposed arrangement, with a common crankshaft between them, in 25 which case two balanced power impulses at each revolution would be produced.

The invention also comprises other features of construction, arrangement and combination of parts, all as hereinafter fully described, and specifically pointed out in the 30 appended claims, reference being made to the accompanying drawings which show two embodiments of the invention, the first comprising an engine having cylinders in tandem or 35 opposed arrangement and the second a single cylinder engine.

In these drawings Fig. 1, is a central vertical section of the first embodiment and Fig. 2 is another central vertical section in a plane 40 at right angles to Fig. 1. Figs. 3-6 are cross sections on lines 3-3, 4-4, 5-5, 6-6, respectively of Figs. 2 and Fig. 7 is a vertical central section of the alternative embodiment referred to above.

45 To first refer to the construction of Figs. 1-6 the engine shown comprises an outer stationary cylinder 1 which is water-jacketed, as at 2 with inlets and outlets for the circulating water at 3 and 4, this outer cylinder being further provided with transfer passages 5 and ports in its wall as hereinafter described. Within said stationary cylinder 1 are two reciprocating working cylinders 6 also provided with ports hereinafter described, and within each of said reciprocating cylinder operates an ordinary working

piston 7 connected by a piston rod 8 to a common crank shaft 9 suitably with interposed roller bearings 10, this crank shaft being mounted in bearings 11 carried in the walls 60 of the outer stationary cylinder 1 and the space between the two opposed working cylinders constituting a crank case 12.

The crank case end of each reciprocating working cylinder 6 is increased in area as by 65 threading thereon a disc 13 adapted to slide on a machined face on the inside of the outer cylinder 1, by being connected to the crank shaft by means of rods 13^a suitably with interposed roller bearings 13^b, and forming a 70 stepped or truncated pumping or precompression piston. The opposite or head end of each reciprocating working cylinder 6 is also shaped or formed as a pumping or precompression piston as by providing it 75 at its outer end with a threaded bush 14 screwed in from the interior. The cylinder end thus formed in conjunction with a head 15 bolted to the end of the stationary cylinder 1 constitute a precompression 80 chamber 16 and the piston 18 at the crank case end constitutes another precompression chamber 17 the capacity of these chambers being controlled by their respective pistons 14 and 13 and each chamber being 85 connectable to the interior of the reciprocating working cylinder by means of transfer passages and ports. Either or both of said compression chambers can be used for the compression of the charge or scavenging 90 air, and the reciprocating cylinder acts as a sleeve valve and controls said ports in manner or phase hereinafter described starting from the head 15 or outer end of the cylinder, namely, inlet of charge to the outer or 95 head compression chamber 16, transfer of charge and scavenging air from the compression chamber 16, 17 to the working cylinder 6, exhaust of gases from the latter and inlet of scavenging air to the inner or base compression chamber 17.

To now describe the port arrangement, 18 designates the induction for the charge as from a carburetter as usual, and which communicates with a series of annular inlet ports 105 19 (see also Fig. 3) in the outer end of the fixed cylinder 1 and leading to the head compression chamber 16, this latter chamber being provided with a mixture transfer passage 20 adapted during the operation of the engine 110 to convey the mixture to the combustion space 21 of the reciprocating working cylinder.

der 6 through transfer inlet ports 22 (see also Fig. 4). The outer end of the fixed cylinder 1 is also provided with a series of scavenging air ports 23 which are adapted to communicate with the transfer passage 5 leading to the base compression chamber 17. The reciprocating working cylinder 6 is provided with inlet ports 24 and 23^a (see also Fig. 4) adapted to communicate during the operation of the engine with the transfer inlet ports 22 and the scavenging air inlet ports 23 respectively. Finally at this end, the outer cylinder 1 is apertured for the reception of diametrically opposed ignition plugs 25 adapted during the operation of the engine to communicate with the combustion space 21 of the working cylinder through ports 26 in the wall of the latter (see also Fig. 5). By this construction it will be seen that the ignition ports are protected or shrouded during a large portion of the working stroke.

At the base or crankcase end the outer cylinder 1 is provided with a series of exhaust ports 27 adapted to communicate during the operation with other exhaust ports 28 in the wall of the working cylinder 6 and communicating with a common exhaust manifold 29 (see also Fig. 6). The said exhaust ports 28 also however serve as inlet ports for scavenging air from the crank case 12 to the inner or base compression chamber 17 to be ultimately carried by transfer passage 5 and ports 23, 23^a to the working cylinder. By thus serving as inlets for the scavenging air the exhaust ports 28 are cooled to a considerable extent.

With the parts constructed and arranged as above described and assuming as shown at the upper ends of Figs. 1 and 2, that the parts are in position when the explosion of the charge takes place, the piston 7 is at the inner or top end of its stroke, and the reciprocating cylinder is at the outer or lower end of its stroke, the said piston and cylinder always moving in opposite directions.

The ports 19 communicating with the head compression chamber 16 and the ports 28 communicating with base compression chamber 17 are open allowing air to pass from the crank chamber 13 to said compression chamber 17 and the charge from the induction 18 to the head compression chamber 16. Under force of explosion the piston 7 moves outwards and the reciprocating cylinder inwards, during which movement the piston disc 13 compresses air in chamber 17 and the bush 14 compresses the charge in chamber 16. At the end of the power stroke the combined movement of cylinder 6 and piston 7 causes the parts to assume the positions shown at the lower end of Figs. 1 and 2 in which the ports 27, 28 are opened for the exhaust of burnt gases and the movement of the cylinder alone opens the scavenging air ports 23, 23^a and the mixture inlet ports 22, 24 at the head

or outer end of the working cylinder; but all these ports are so proportioned that they are opened in the following sequence, namely, first exhaust, followed by scavenging and finally admission of mixture.

On the return stroke the combined movements of piston 7 and reciprocating cylinder 6 compress a new charge admitted to chamber 16 and the movement of the cylinder alone creates depression in the compression chambers, until the relative ports are again opened to permit inlet of scavenging air and charge.

In the second or alternative embodiment illustrated in Fig. 7 the same general arrangement and construction is observed but the charge is transferred to the working cylinder only through ports 30, 30^a at the outer end or heads of the working and stationary cylinders respectively and the exhaust from the cylinder and transfer of scavenging air there-to takes place through ports 31, 32 respectively at the crank case end. In this figure the remaining reference characters designate corresponding parts to those used with reference to Figs. 1 to 6.

The working and precompression portions of the reciprocating cylinder 6 may be made of any desired capacity and the relative speeds of the piston and said cylinder may be such or be so controlled as to obtain the highest efficiency, for example the ports at the crank case or lower end of the cylinder may be opened at the full combined speed of the piston and reciprocating cylinder and the ports at the outer or top end at the speed of the reciprocating cylinder only, or by offsetting or suitably arranging the crankshaft the ports at either end of the working cylinder may be caused to open and close in any required relation to each other.

The compression ratio of the charge or head compression chamber may also be variable for instance by extending the bore of the stationary cylinder and providing it with an adjustable plug, plunger or equivalent operated for example in conjunction with the main throttle valve whereby the ratio may be increased as the throttle is opened.

It will also be apparent from the above description that the precompression of the charge and air and the control of the ports is effected without complicated internal mechanism. Surplus of air compressed in the base or inner chamber may be available for operating the brakes, horn, windscreens-wiper or signalling devices or for inflating the tires of a motor vehicle with which such an engine may be used and if used in conjunction with a reservoir also for operating a self-starter. Such compressed air might also be used for force-feed of fuel and supply of lubricant to different parts of the engine and chassis thus permitting a lubricant pump to be dispensed with.

What I claim as my invention and desire to secure by Letters Patent of the United States is:—

1. In a two stroke cycle internal combustion engine the combination of a crank shaft, a crank case, a stationary cylinder radial to the shaft, having its bore enlarged at the inner end to form a compression chamber, and having also a compression chamber at the outer end, a piston cylinder slideable in said stationary cylinder, having a pumping member working in said inner compression chamber, and having a head at its outer end, a piston in said piston cylinder, and means connecting said piston cylinder and said piston respectively to said shaft, for imparting rotation to said shaft by reciprocation in opposite directions, said stationary cylinder having transfer ducts, and said cylinders having ports controlled by movements of said piston cylinder and piston respectively, whereby

while said piston cylinder is moving towards said shaft air is admitted to said inner compression chamber and combustible mixture is admitted to the outer compression chamber, and while said piston cylinder is moving towards said outer compression chamber said mixture and said air are compressed, and ports are opened for exhaust from the space between said piston and the head of said piston cylinder, and the compressed air is admitted to said space, and then the compressed mixture is admitted to said space.

2. The combination claimed in claim 1, the piston cylinder having for the admission of air to the inner compression chamber ports which serve also as ports for exhaust from the space between the piston and the head of said piston cylinder.

In witness whereof I have signed this specification.

WILLIAM ALLAN.
